PRINTING MECHANISM

Harry L. Lambert, Enfield, N. Y., assignor to
 Allen Wales Adding Machine Corporation,
 Ithaca, N. Y.

Application December 27, 1940, Serial No. 371,888

9 Claims. (Cl. 197—153)

This invention relates to the printing of characters upon paper strips, and particularly to the printing through a plurality of inked ribbons upon a plurality of sheets of paper simultaneously by a common set of type. Devices of this type are useful in typewriting and adding machines where it is desirable to print simultaneously upon a plurality of paper sheets with a plurality of ribbons so as to make a plurality of ribbon copies of the typed matter.

An object of this invention is to provide improved means for simultaneously printing a plurality of copies through a plurality of inked ribbons.

Another object of the invention is to provide improved means for printing upon a plurality of superposed sheets, backed by a platen, simultaneously by individual, inked ribbons.

Another object of the invention is to provide improved means for printing a plurality of ribbon copies simultaneously, and also to provide improved means for feeding the sheets to be printed upon through proper printing relation with respect to a plurality of ribbons, the sheets to be printed upon, and the platen, with which the assembly of the superposed sheets and the ribbons in printing relation to one another and to the platen is facilitated.

A further object of the invention is to provide improved means for printing a plurality of ribbon copies simultaneously with a single printing device, with which the assembly of the sheets to be printed upon and the ribbons and the platen may be easily and speedily accomplished, which will be relatively compact, which will not greatly increase the mechanism required, which may be readily adapted to various types of typewriter and adding machines without greatly altering their present designs, and which will be relatively simple and inexpensive.

Other objects and advantages will be apparent from the following description of one embodiment of the invention, and the novel features will be particularly pointed out hereinafter in connection with the appended claims.

In the accompanying drawings:

Fig. 1 is a perspective of the printing mechanism of an adding machine in which my invention is incorporated;

Fig. 2 is a perspective of a portion of the same, the view being taken from the rear, adjacent one end of the platen, and with a portion of the platen broken away to show details otherwise concealed thereby;

Fig. 3 is a diagram, something in the nature of

a sectional plan through the ribbons at one end of the platen, illustrating the manner in which the ribbons are kept separate from one another in the printing zone;

5 Fig. 4 is a rear elevation of the ribbon supports and guides, with the platen removed;

Fig. 5 is a sectional plan through the adding machine, with the platen, guard and ribbon unsectioned, the section being taken immediately 10 beneath the top flanges of the ribbon spools;

Fig. 6 is a transverse sectional elevation through the parts shown in Fig. 5, the section being taken approximately along the line 6—6 of Fig. 5;

15 Fig. 7 is a sectional elevation through the mechanism of Fig. 5, on a scale double that used in Figs. 5 and 6, the section being taken approximately along the line 7—7 of Fig. 5, but with the ribbon guard elevated to illustrate one 20 step in the process of inserting the sheets to be typed upon, into proper printing relation to the ribbons;

Fig. 8 is a sectional elevation similar to Fig. 7, but with the ribbon guard in its lowered position, 25 which is the position normally occupied, which represents another step in the positioning of the paper sheets in proper printing relation to the platen and the ribbons, it being understood that the platen has been rotated in a feeding direction somewhat from the position shown in Fig. 7; and

Fig. 9 is a side elevation, on the scale of Fig. 5, of the spool mounting and driving means, with the position of the spool thereon shown by dash lines.

35 In the illustrated embodiment of the invention, the machine selected for illustration, and in which the improvements are incorporated, is an ordinary adding machine. It will be understood that the invention is also applicable, in its

40 broader construction, to other machines in which printing is done through inked ribbons, such as, for example, typewriters and cash registers. In this example, the paper sheets are confined in superposed, face to face relation against a platen

45 10 of cylindrical type, which platen is mounted for rotation about its longitudinal axis by means of its shaft 11 which is rotatably confined in suitable bearings (not shown) in the platen frame 12. The shaft 11 is provided at one end

50 with a knob 13 by which the platen may be rotated manually for line spacing, as usual. The platen shaft 11 is also provided with a ratchet wheel 14 by which the platen may be given increments of rotation by automatic mechanism controlled by the printing mechanism in an add-

ing machine, or by automatic or manually operable line-spacing mechanism in typewriting machines. Such details are common in adding and typewriting machines and in themselves form no part of this invention.

Disposed immediately in front of, and extending in a direction lengthwise of, the platen, is a ribbon guard and guide or support 15. This guard 15 is guided for limited vertical movement in any suitable manner. In the example illustrated, the guard is provided with depending arms 16 which fit against faces of two plates 17 forming parts of the machine frame. Each arm 16 is provided with a vertical slot 18, which straddles the shank of a screw 19 that is threaded into the adjacent frame plate 17. The head of each screw 19 confines its related arm 16 to the adjacent fixed plate 17. Each plate 17 has an upstanding lug 20 along which the adjacent arm 16 extends, and each arm 16 is further provided with a second vertical slot 21 through which extends a screw 22 carried by the adjacent lug 20, the head of which retains the arm 16 in contact with the face of the lug. The slots 18 and 21 of the arms 16 are so disposed with respect to the screws 19 and 22 that the arms 16 and ribbon guard 15 are permitted a limited vertical movement relatively to the two fixed plates 17. Any other means for supporting the guard 15 and guiding it for such vertical limited movement may be employed.

In front of the guard is a combined ribbon and spool supporting frame 24 (Fig. 1) which is also independently guided for limited vertical movement in a manner common in machines of this type. This spool and ribbon supports has approximately parallel, upstanding arms 25 to the upper ends of which are secured members 26, the vertical arms of which extend into close proximity to the guard 15. That edge of each vertical arm of member 26, which is adjacent the guard 15, is provided with a notch 27, and an inked ribbon 28 is disposed in the notches 27 and stretched between these vertical arms of members 26 as shown in Fig. 1. A spool shaft 29 is fixed to and projects upwardly from the horizontal arm 30 of each member 26, each shaft having a threaded recess in its upper end. The ribbon 28 extends between and at its ends is mounted upon ribbon spools 31 which are removably and rotatably mounted upon the spool shafts 29.

Rotatably confined upon each spool shaft 29, such as by a downwardly facing shoulder on the shaft, is a sleeve 32 having fixed to its lower face a ratchet or gear wheel 33 by which the sleeve 32 may be given increments of rotation. A pin 34 projects upwardly from the upper end face of the sleeve 32 and removably enters an aperture in the lower flange of the ribbon spool which may be fitted over the shaft 29 so that the spool will be rotated from the sleeve 32 and the pin 34. Rotatably confined between the wheel 33 and the horizontal arm of the member 26 is a bell crank arm 35 which may oscillate independently of the wheel 33. The wheel 33 for each spool is given increments of rotation by the usual ribbon feeding mechanism, not shown. One arm of each bell crank 35 is connected by a tension spring 36 to the adjacent end of the guard 15, so as to urge the bell cranks 35 as indicated by arrows in Fig. 5. The other arm of each bell crank 35 has an upstanding end 37 which engages with a side face of the ribbon 28 and tends to pull on that ribbon under the pressure exerted by the spring 36 in an effort to keep taut the portion of said ribbon between said spools.

A suitable frictional brake (not shown) acts upon the hub of each sleeve 32 to exert a slight drag thereon as usual in this type of machine. A second inked ribbon 38 has its ends connected 5 to the same spools 31 along with the ends of the other ribbon 28, so that the corresponding ends of both ribbons will be wound upon the same spools in superposed, face to face relation to one another. The ribbons are also preferably of approximately the same length. The ribbon 38 extends from each spool to the end of the guard 15 and is supported in and guided by a notch 39 in each end of the guard, the ribbon then passing 10 along that face of the guard towards the platen, and across the aperture or open window 40 in the guard at the same vertical level as the portion of the ribbon 28 which extends between the notches 27 in the supports 26.

Attached to that face of the guard towards the 20 platen 10 are one pair of upstanding spring fingers 41 (Figs. 2, 3, and 4) which are connected together at a zone well below their upper free ends by a cross bar 42. The fingers 41 are secured at their lower ends to the guard 15, and their upper ends are normally spaced slightly 25 from the guard as shown in Fig. 3. Additional fingers 43 are disposed between the spaced fingers 41 and secured at their lower ends to the same face of the guard, but extend upwardly into approximately the same plane as the free ends of 30 fingers 41 (also shown in Fig. 3). The ribbon 38, after passing through the notches 39 in the ends of the guard 15, passes first between the guard and the fingers 41, and then between the platen and fingers 43 at each end of the platen. This 35 produces sufficient frictional drag on the ribbon 38 to keep it taut in the zone which extends across the window 40 of the guard. It will be noted that the zones of the two ribbons which 40 extend across the window 40 of the guard are disposed in face to face, approximately parallel relation, but slightly spaced apart.

Two sheets of paper 44 and 45 are fed from suitable rolls or magazines (not shown) in superposed relation to one another over a guide 46 (Fig. 8) and then between the guide 46 and the platen 10, so as to pass beneath the platen and towards the guard 15. These superposed sheets of paper are yieldingly urged against the under 50 face of the platen by any suitable mechanism such as rubber rollers 47 (see Figures 6 and 8), these rollers being carried by a frame 49 (Fig. 6) which is pivoted at 50 to a pair of levers 51 which, in turn, are fixed upon a shaft 52 having at one 55 end a handle or arm 53. Mechanism of this type suitable for confining the paper strips to the platen is very common in the art, and its details per se form no part of this invention. From the rollers 47 the paper strips or sheets 44 and 45 60 are fed toward the guard 15. The strip 44, which is in contact with the platen, passes upwardly between the ribbon 28 and the platen, and strip 45 passes beneath the cross bar 42 which connects the fingers 41, and upwardly between the 65 ribbons.

In order to facilitate the insertion of the paper strips 44 and 45 in the proper position with respect to the ribbons and the platen, the leading end edge of the sheet or strip 45 is advanced 70 somewhat further than the leading end edge of the other sheet in starting them over the guide 46, as will appear from Figs. 7 and 8. As the platen 10 is rotated to feed the strips of paper around until the leading ends approach the guard 75 15, the leading end of the outer sheet 45 will

move somewhat tangentially to the platen 10 until it reaches the guard 15 when the leading end will be deflected upwardly thereby. When the guard 15 is in its lowermost position, as shown in Fig. 8, the lower edge of the cross bar 42 is normally below the path of the leading end of the paper 45 as it approaches the guard 15, and it would normally be deflected upwardly by the cross bar 42 into a position between the platen and the ribbon 38.

This guard 15 is shifted upwardly into its upper position, as shown in Fig. 7, before the leading end of the sheet 45 is fed toward the guard, so that the lower edge of the cross bar 42 will be above the path of travel of the leading end of sheet 45 approaching the guard 15 in an upwardly inclined direction from the last rollers 47. This leading end of sheet 45 will thus pass beneath the cross bar 42 and strike the guard 15 and be deflected upwardly thereby, behind the bar 42, so as to move upwardly between the two ribbons. When the guard 15 is shifted downwardly into the position shown in Fig. 8, continued movement of the platen will feed the other strip 44 towards the guard, but its leading end edge will strike the cross bar 42 and be deflected upwardly thereby, between the ribbon 38 and the platen.

To aid in this separation of the two strips, the lower edge of the cross bar 42 is preferably provided with a flange 55 which extends generally toward the last rollers 47. This flange, when the guard 15 is in its upper position, as shown in Fig. 7, is in close proximity to the surface of the platen, and tends to deflect to the front of the cross bar the leading end edge of the sheet or strip 45 which approaches the guard, if the paper sheet should happen to cling or swerve somewhat toward the platen. When the flange 55 is in its lowermost position, as shown in Fig. 8, it tends to deflect upwardly and toward the platen, the leading end edge of the sheet 44 which approaches the guard, if such sheet tends to veer away from the platen after leaving the last rollers 47. The flange is thus shifted across the path of travel of the leading ends of the paper strips.

The guard 15 is yieldingly urged into its lowermost position, shown in Fig. 8, in any suitable manner, such as by springs 56 which are anchored in any suitable manner, such as to the ribbon spool supports 26, and extend through apertures in the lower edge portion of the guard 15. To facilitate lifting or upward movement of the guard 15, I also preferably provide a shaft 57 which extends in a direction parallel to the platen in a position between the guard and the platen, but just below the normal path of travel of the leading end edges of the paper sheets 44 and 45 leaving the last of the rollers 47, as shown clearly in Fig. 8. An operating handle 58 is provided upon one end of the shaft 57 to enable limited rocking movement thereof. Intermediate of its ends, the shaft 57 is provided with arms 59 which are fixed thereon and extend through apertures 60 in the lower part of the guard 15. Hence, by rocking the shaft 57 in a clockwise direction in Figs. 6-8, the arms 59 will shift the guard 15 upwardly from the normal position shown in Fig. 8 to the temporary position shown in Fig. 7 and against the action of the springs 56. As soon as the handle 58 is released, the springs 56 will shift the guard back into its lowermost, normal position.

A tear-off bar 61 is secured to the upper edge

of the guard 15 so as to bridge the opening or window 40, and this bar preferably has a serrated upper edge to serve as a tear-off edge. The sheets or strips of paper 44 and 45, after passing upwardly past the ribbons, may be torn off whenever desired, by tearing off the same against the serrated edge of the bar 61. This tear-off bar is preferably also made of transparent material, such as of a moldable, transparent resin, a number of which are available in the open market under different trade names, and one of which is chemically known as methyl methacrylate resin. By having the tear-off bar of transparent material, the entire zone of the sheet or strip 45 on which printing may have been done in accordance with this invention, will be visible after it passes upwardly above the ribbons 28 and 38.

Suitable printing mechanism is provided for printing through the ribbons upon the sheets 44 and 45, and while this mechanism may be of any suitable kind in which type bearing characters are struck against the ribbon 28 in a direction toward the platen, I have shown in the drawings the printing mechanism of the ordinary adding machine in which the type bars 62 are disposed side by side along the platen and are elevated individually by suitable mechanism (not shown) to selected heights in printing position in front of the ribbon 28. Each type bar carries a plurality of type elements 63 which are arranged in a vertical row and mounted for individual sliding movement toward and from the ribbon 28. Suitable mechanism (not shown) such as a hammer ball, is arranged to strike those type elements 63 which have been positioned in a particular horizontal row by selective elevation of the type bars to different extents, and drive the same against the ribbon 28 and towards the platen 10. This impact of the type elements 63 against the ribbon 28 prints the characters of those type elements through both of the ribbons upon the paper sheets, as well known in typewriters and adding machines.

In the operation of the illustrated embodiment of the invention, the inked ribbons 28 and 38, which are of approximately the same length, have their corresponding ends connected to the spools 31 and partially wound thereon, with an intermediate zone of each ribbon extending across the window 40 in the guard 15, immediately in front of the type bars 62. The paper strips or sheets 44 and 45 are arranged at their leading ends in superposed relation to one another and fed downwardly between the guide 46 and the platen 10, with the leading end edge of the sheet 45 advanced somewhat ahead of the leading edge of the sheet 44, as shown in Figs. 7 and 8. The platen is then rotated in a clockwise direction in Figs. 7 and 8, which carries the leading end of the sheet 45 towards the guard 15. The handle 58 is rocked in order to elevate the guard 15 from the Fig. 8 to the Fig. 7 position, by which movement the flange 55 is disposed above the normal path of the leading end of the sheet 45, with the result that such leading end will pass to the front of the flange 55 and be deflected by the guard 15 upwardly between the ribbons 28 and 38.

As soon as the leading end edge of the sheet 45 passes upwardly between the ribbons, the handle 58 is released, whereupon the springs 56, assisted by gravity, return the guard 15 to its lowermost position, shown in Fig. 8, and then the platen 10 is rotated further in the same direction. The leading end edge of the sheet 44 then passes be-

tween the platen and the ribbon 38, as shown in Fig. 8. To facilitate insertion of the paper, the handle 53 may, of course, be rocked in order to shift the rollers 47 out of contact with the platen, as usual in adding machines and typewriters. The type bars 62 are individually set by the adding machine mechanism (not shown) into different elevations selectively, and then at the conclusion of the operation, those type elements 63 which have been arranged in a particular row along the ribbon 28 by the selective elevation of the type bars 62, will be struck and driven toward the ribbon 28 with sufficient force to print from the ribbon 28 upon the paper sheet 45, and by the impression through the paper 45 print from the ribbon 38 upon the under sheet 44, thus making two inked ribbon or primary copies.

At successive operations of the printing mechanism, the spools 31 are given increments of rotation in one direction or the other, as usual in adding and typewriting machines, in order to feed the ribbons from one spool to the other, with suitable reversing mechanism operable at intervals to reverse the direction of travel from spool to spool. It will be noted that the unwound portions of the ribbons travel in different paths with different lengths, and the bell crank levers 35, serve to take up any slack in the ribbon 28 having the shorter path and keep that ribbon taut in the zone extending through printing position in front of the window 40 of the guard. After the desired amount of printing has been performed, the paper strips may be torn off along the serrated upper edge of the bar 61.

It will be understood that various changes in the details which have been herein described and illustrated in order to explain the nature of the invention, may be made by those skilled in the art within the principle and scope of the invention as expressed in the appended claims.

I claim as my invention:

1. In a machine for printing characters upon a plurality of superposed sheets simultaneously, the combination of a platen mounted for rotation about its longitudinal axis, a pair of inked ribbons, a ribbon guard disposed to extend along one side face of the platen in proximity thereto but spaced slightly therefrom and mounted for independent, limited vertical movement, said guard having means for guiding and disposing one of said ribbons in superposed, face to face relation to, but slightly spaced from, the other ribbon, and along said side face of said platen, and means for confining said sheets against the underside of said platen to be advanced therewith towards said guard and upwardly between the guard and platen, said guard having an angular depending flange running in a direction approximately parallel to the length of the platen, disposed below the lower edge of said guard guided ribbon, and extending toward the platen, said confining means guiding the advancing end edges of said strips towards said guard and upwardly to normally engage said guard above said flange when said guard is in its lowermost position, and below said flange when the guard is in its elevated position, said flange being disposed to guide a paper sheet striking the guard below said flange between said ribbons and guide a paper sheet striking the guard above it, upwardly between the platen and ribbon nearest the platen.

2. In a machine of the type for printing upon a pair of superposed sheets of paper simultaneously, the combination which comprises a platen, a pair of inked ribbons, means for supporting

said ribbons in superposed, spaced relation in a printing position adjacent said platen, a pair of generally parallel spaced apart plates, means for advancing said sheets in a direction obliquely and generally towards said plates, one of said plates extending outwardly beyond the other, and said plates being mounted for selective movement into two positions in one of which said outwardly extending plate alone is in the path of an advancing sheet in a position to deflect that sheet, and in the other of which the other of said plates is operable to deflect the edge of an advancing sheet, whereby the ends of a pair of advancing sheets may be selectively deflected and separated, means for guiding separated sheets into printing positions in which one of said sheets is between said ribbons and the other of said sheets is between said platen and the two ribbons, and means for printing on said sheets through said ribbons and against said platen.

3. In a machine for printing characters upon a plurality of superposed sheets simultaneously, the combination of a platen mounted for rotation about its longitudinal axis, a pair of inked ribbons, a ribbon guard disposed to extend along one side face of the platen in proximity thereto but spaced slightly therefrom and mounted for independent limited vertical movement, said guard having means for disposing said ribbons in superposed, face to face relation but slightly spaced apart, and along said side face of said platen, means for confining said sheets against the underside of said platen to be advanced therewith towards said guard and upwardly between the guard and platen, said guard having a flange running in a direction approximately parallel to the length of the platen and extending toward the platen at a point slightly below a horizontal plane through the axis of rotation of the platen, said confining means guiding the advancing end edges of said strips towards said guard and upwardly to normally engage said guard above said flange when said guard is in its lowermost position, and below said flange when the guard is in its elevated position, said flange being disposed to guide a paper sheet striking the guard below said flange between said ribbons and guide a paper sheet striking the guard above it, upwardly between the platen and ribbon nearest the platen, a shaft disposed to extend approximately parallel to said platen, means carried by said shaft and engageable with said guard to impart thereto said limited vertical movement in one direction, upon rocking of said shaft, and means on said shaft by which it may be rocked when vertical movement of said guard is desired.

4. In a machine for printing characters upon a plurality of superposed sheets simultaneously, the combination of a platen mounted for rotation about its longitudinal axis, a pair of inked ribbons, a ribbon guard disposed to extend along one side face of the platen in proximity thereto but spaced slightly therefrom and mounted for independent limited vertical movement, said guard having means for disposing said ribbons in superposed, face to face relation but slightly spaced apart, and along said side face of said platen in the printing zone thereof, and means for confining said sheets against the underside of said platen to be advanced therewith towards said guard and upwardly in a direction between the guard and platen, said guard having a flange running in a direction approximately parallel to the length of the platen and extending toward

the platen at a point slightly below the printing zone of the platen, said confining means guiding the advancing end edges of said strips towards said guard and upwardly to normally engage said guard above said flange when said guard is in its lowermost position, and below said flange when the guard is in its elevated position, said flange being disposed to guide a paper sheet striking the guard below said flange between said ribbons and guide a paper sheet striking the guard above it, upwardly between the platen and ribbon nearest the platen.

5. In a machine for printing characters upon a plurality of superposed sheets to make a plurality of copies simultaneously, the combination of a platen mounted for rotation about its longitudinal axis, a pair of inked ribbons disposed in face to face and slightly spaced relation to one another along a side of, but slightly spaced from, said platen, means for confining said sheets against a portion of said platen and releasing said sheets as they approach said ribbons upon rotation of said platen in one direction, a deflector disposed approximately in the path of travel of the advancing ends of said sheets as they are released by said confining means, and adjacent corresponding edges of said ribbons nearest said advancing ends of said released sheets, means for shifting said deflector across the path of said advancing ends of said released sheets while both ribbons remain along and in proximity to the same side of the platen and operable when in one position to guide an advancing end of the outer one of said released sheets between said ribbons, and in another position to guide an advancing end of the other of said released sheets between said platen and the ribbon nearest said platen, type mechanism operable against the ribbon farthest from the platen in a direction toward the platen, and means carried by the carriage and engageable with the deflector for shifting it between said positions, said shifting means having an operating handle adjacent an end of the carriage by which it may be operated.

6. In a machine for printing characters upon a plurality of superposed sheets to make a plurality of copies simultaneously, the combination of a platen mounted for rotation about its longitudinal axis, a pair of inked ribbons disposed in face to face and slightly spaced relation to one another along a side of, but slightly spaced from, said platen, means for confining said sheets against a portion of said platen and releasing said sheets as they approach said ribbons upon rotation of said platen in one direction, a deflector disposed approximately in the path of travel of the advancing ends of said sheets as they are released by said confining means, and adjacent corresponding edges of said ribbons nearest said advancing ends of said released sheets, means for shifting said deflector across the path of said advancing ends of said released sheets while both ribbons remain along and in proximity to the same side of the platen and operable when in one position to guide an advancing end of the outer one of said released sheets between said ribbons, and in another position to guide an advancing end of the other of said released sheets between said platen and the ribbon nearest said platen, type mechanism operable against the ribbon farthest from the platen in a direction toward the platen, and means for yieldingly urging said deflector into said another position.

7. In a machine for printing characters upon a plurality of superposed sheets to make a plurality of copies simultaneously, the combination of a platen mounted for rotation about its longitudinal axis, a pair of inked ribbons disposed in face to face and slightly spaced relation to one another along a side of, but slightly spaced from, said platen, means for confining said sheets against a portion of said platen and releasing said sheets as they approach said ribbons upon rotation of said platen in one direction, a frame, type mechanism on said frame for striking said ribbons to print on said sheets against said platen, and a guide for the ribbon nearest the platen for guiding that ribbon in a direction lengthwise of the platen past printing position of said type mechanism on said platen, said guide having depending legs engaging said frame for limited movement in a direction crosswise of the direction of travel of the ribbons through said printing position, while the ribbons remain along and in about the same proximity to the same side of the platen, said guide having a deflector portion slightly below said printing position to aid in threading said sheets through printing relation with respect to said platen and ribbons, through such limited movement, as the leading edges of said sheets advance in sequence towards said deflector portion.
- 10 8. In a machine for printing characters upon a plurality of superposed sheets to make a plurality of copies simultaneously, the combination of a platen mounted for rotation about its longitudinal axis, a pair of inked ribbons disposed in face to face and slightly spaced relation to one another along a side of, but slightly spaced from, said platen, means for confining said sheets against a portion of said platen and releasing said sheets as they approach said ribbons upon rotation of said platen in one direction, a frame, type mechanism on said frame for striking said ribbons to print on said sheets against said platen, and a guide for the ribbon nearest the platen for guiding that ribbon in a direction lengthwise of the platen past printing position of said type mechanism on said platen, said guide having depending legs engaging said frame for limited movement in a direction crosswise of the direction of travel of the ribbons through said printing position, while the ribbons remain along and in about the same proximity to said platen, said guide having a deflector portion slightly below said printing position to aid in threading said sheets through printing relation with respect to said platen and ribbons, through such limited movement, as the leading edges of said sheets advance in sequence towards said deflector portion.
- 15 9. In a machine for printing characters upon a plurality of superposed sheets to make a plurality of copies simultaneously, the combination of a platen mounted for rotation about its longitudinal axis, a pair of inked ribbons disposed in face to face and slightly spaced relation to one another along a side of, but slightly spaced from, said platen, means for confining said sheets against a portion of said platen and releasing said sheets as they approach said ribbons upon rotation of said platen in one direction, a frame, type mechanism on said frame for striking said ribbons to print on said sheets against said platen, and a guide for the ribbon nearest the platen for
- 20 10 11 12 13 14 15 16 17 18 19 20 21 22 23 24 25 26 27 28 29 30 31 32 33 34 35 36 37 38 39 40 41 42 43 44 45 46 47 48 49 50 51 52 53 54 55 56 57 58 59 60 61 62 63 64 65 66 67 68 69 70 71 72 73 74 75

guiding that ribbon in a direction lengthwise of the platen past printing position of said type mechanism on said platen, said guide having depending legs engaging said frame for limited movement in a direction crosswise of the direction of travel of the ribbons through said printing position, while the ribbons remain along the same side of said platen, said guide having a deflector portion slightly below said printing position to aid in threading said sheets through 10

printing relation with respect to said platen and ribbons, through such limited movement, as the leading edges of said sheets advance in sequence towards said deflector portion, means yieldingly urging said guide toward one limit of its limited movement, and manually controlled means for moving said guide against the action of said urging means toward its other limit of said movement.

HARRY L. LAMBERT.
